CLAIM

I claim the ornamental design for a nozzle for a liquid or foam pump, as shown and described.

DESCRIPTION

FIG. 1 is a perspective front view of the nozzle for a liquid or foam pump, showing my new design,

FIG. 2 is a front view thereof,

FIG. 3 is a right side view thereof, the left side view being a mirror image thereof,

FIG. 4 is a bottom view thereof; and,

FIG. 5 is top view thereof.

1 Claim, 4 Drawing Sheets

FIG. 1

FIG. 2

FIG. 3

FIG. 4

FIG. 5

UNITED STATES PATENT AND TRADEMARK OFFICE
CERTIFICATE OF CORRECTION

PATENT NO. : D673,850 S
APPLICATION NO. : 29/405345
DATED : January 8, 2013
INVENTOR(S) : Michael Wadt

Page 1 of 1

It is certified that error appears in the above-identified patent and that said Letters Patent is hereby corrected as shown below:

On the title page, item no. 73 should read:

Assignee: Hygiene Vision Ltd., Stamford, Lincolnshire (GB)

Signed and Sealed this
Fifth Day of November, 2013

Teresa Stanek Rea
Deputy Director of the United States Patent and Trademark Office

UNITED STATES PATENT AND TRADEMARK OFFICE
CERTIFICATE OF CORRECTION

PATENT NO. : D673,850 S
APPLICATION NO. : 29/405345
DATED : January 8, 2013
INVENTOR(S) : Michael Wadt

Page 1 of 1

It is certified that error appears in the above-identified patent and that said Letters Patent is hereby corrected as shown below:

On the title page, item (75) Inventor

“Michael Wadt, Jyllinge (DK)”

should read as follows:

--Michael Wadt, Jyllinge (DK)--

On the title page, item (73) should read:

--Assignee: Hygiene Vision Ltd., Stamford, Lincolnshire (GB)--

This certificate supersedes the Certificate of Correction issued November 5, 2013.

Signed and Sealed this
Tenth Day of December, 2013

Margaret A. Focarino
Commissioner for Patents of the United States Patent and Trademark Office
